UNITED STATES PATENT OFFICE.

JOHN ABSTERDAM, OF NEW YORK, N. Y., ASSIGNOR TO NATHAN & DREYFUS, OF SAME PLACE.

APPARATUS FOR LUBRICATING THE CYLINDERS AND BEARINGS OF STEAM-ENGINES.

SPECIFICATION forming part of Letters Patent No. 237,715, dated February 15, 1881.

Application filed January 3, 1881. (No model.)

To all whom it may concern:

Be it known that I, JOHN ABSTERDAM, of the city, county, and State of New York, have invented certain new and useful Improvements in Apparatus for Oiling or Lubricating the Cylinders and Bearings of Steam-Engines, and for other purposes, of which the following is a specification.

My improvement has special reference to that kind of lubricator in which the feed of the oil is disclosed by the upward passage of the oil-drops through a body of water contained in a glass or other transparent receiver; and it consists in the construction and arrangement of the several parts of the lubricator, as hereinafter described.

In the accompanying drawings, Figure 1 is a vertical central section of a lubricator embodying my improvement.

20 A is a metallic oil-receiving chamber, carrying on one side an external glass gage, B, opening at the top into the interior of the chamber, and at the bottom into the waste-passage *a* of the plug C, which is also provided with a 25 branch passage, *b*, in communication with a discharge-passage, *b'*, leading from the bottom of the chamber A. The glass tube which constitutes this gage has a packing at each end, and is pressed up into its upper bearing and 30 held tightly in place with sealed joints by means of plug C, which screws into a bearing up against the lower end of the gage-tube, as shown plainly in the figure. The discharge-passage *a* is controlled by a waste-cock, *c*. 35 The lateral extension from the oil-chamber, in which the upper end of the gage is seated, is prolonged in an upward direction to form a bearing, D, into which the lower end of the vertical tube E is screwed. The oil is supplied 40 to the chamber A through the upper end of this tube, which is closed, as shown, by a packed removable cap, F. The tube E thus becomes virtually an extension of the oil-chamber A, and is intended to receive within 45 it the oil-feed tube G. The upper end of this tube is located in the upper portion of the said vertical extension. The oil-feed tube thence extends downward into the body of the oil-chamber, and thence extends upward, so as to 50 project through and a little above the head of

said chamber and into the lower portion of the glass dome H, which is secured in place on top of the oil-chamber by means of a nut, I, which surrounds it and screws into a bearing, J, on the oil-chamber.

55

The end G' of the oil-feed tube constitutes a nozzle from which the oil is discharged, and passes up through the body of water with which the glass dome is to be partly filled.

From the upper portion of the glass dome 60 extends the oil-discharge tube K down through the oil-chamber A, and into a passage, *d*, in the plug L, which is screwed into the bottom of the oil-chamber. The drops of oil discharged from the nozzle G gather upon the surface of 65 the water in the glass dome, and thence pass over into the upper end of the oil-discharge tube K, through which tube and the pipe or pipes connected with the lower end of the same the oil is conducted to the parts to be 70 lubricated.

By reason of the extension E, I am enabled to carry the upper end of the oil-feed tube—that is to say, the point at which the oil descends to the upwardly-turned nozzle G'—75 above the point at which the oil enters the discharge-tube K in the glass dome.

The plug L, in addition to the oil-discharge passage *d*, is provided with a passage, *e*, for the entrance of the water, which raises the body 80 of the oil in the oil-chamber into the extension E high enough to cause it to pass over into the oil-feed tube. The plug is also provided with two tubular branches, L' L², communicating one with the passage *e* and the other 85 with the passage *d*, each being controlled by a separate valve, *e'* and *d'*. The branch L' receives the pipe M, which supplies the water that operates, by its pressure, upon the oil in the oil-chamber, substantially as described in 90 my Letters Patent No. 11,958, of November 21, 1854. The other branch, L², receives the pipe N, which conveys the oil to the parts to be lubricated.

A modification of my improvement is shown 95 in Fig. 2, which is a vertical central section of a lubricating apparatus. In this apparatus the oil-feed tube G, while still having the point at which the oil begins to descend through it to its discharge-nozzle above the point at which 100

the oil in the glass dome passes over into the oil-discharge tube K, is so arranged as to be contained within the glass dome, thus dispensing with the vertical extension E of Fig. 5. I accomplish this result by extending the oil-feed tube G from the top of the oil-chamber up into the upper part of the dome, so as to carry it above the upper end of the oil-discharge tube K; thence down to near the bottom of the glass dome, and thence upward a short distance, so that it may have an upwardly-turned discharge-nozzle, G.

In the apparatus shown in Fig. 2, I dispense with the glass gage, and I put the waste-passage in the plug L between the passages e and d, as indicated at f. With this exception the apparatus shown in Fig. 2 is constructed in the same way as the apparatus shown in Fig. 1.

By having that part of the tube G from which the oil descends to the discharge-nozzle elevated above the upper end of tube K, I am enabled to readily fill the glass dome with water through tube G, and then draw off the water from the cup or chamber A without affecting that in the dome above. The plug or shank

L, constructed with the three separate independently valve-controlled passages, as shown in Fig. 2, affords a convenient and ready means of connecting all the various parts of the apparatus.

Having thus described my improvements, what I claim, and desire to secure by Letters Patent, is—

The oil-chamber A, provided with plug L and separate passages for entrance and escape of water, and the glass dome H, mounted upon and secured to the top of the oil-chamber, in combination with the oil-discharge tube K, extending from the upper part of the glass dome down through the oil-chamber, and the bent oil-feed tube G, having that part from which the oil descends to the discharge-nozzle elevated above the upper end of discharge-tube K, as herein shown and described.

In testimony whereof I have herein to set my hand this 30th day of December, 1880.

JOHN ABSTERDAM.
